UNITED STATES PATENT OFFICE.

BERNARD KERN, JR., OF TOLEDO, OHIO.

ROTARY BRUSH.

No. 857,525.

Specification of Letters Patent.

Patented June 18, 1907.

Application filed July 18, 1904. Serial No. 216,959.

To all whom it may concern:

Be it known that I, BERNARD KERN, Jr., a citizen of the United States, and a resident of Toledo, in the county of Lucas and State of Ohio, have invented certain new and useful Improvements in Rotary Brushes; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in rotary brushes or brooms, and is especially designed in view of the needs of street sweeping machines in which a forced draft is employed in conjunction with a revolving brush or broom to remove the dust and dirt from the surface of the street and deposit the same in a suitable receptacle associated with the machine.

An object of my invention is the provision 25 of an improved construction of brush or broom that is so mounted on its shaft as to permit it to have a lateral movement independent of such shaft whereby to adapt it during rotation to accommodate itself to the 30 changing contour of the surface over which it operates.

A further object of my invention is the provision of improved means within each broom section whereby the rows of fiber brushes may be radially adjusted to compensate for wear, which will be greater on them than on the steel brushes.

A further object of my invention is the provision of simple and efficient means for 40 longitudinally adjusting the broom sections whereby they are placed in proper position for cleaning a gutter or for other purposes.

The operation, arrangement and details of construction of the parts of my invention are 45 fully described in the following specification, and shown in the accompanying drawings, in which,—

Figure 1 is a central longitudinal section of the brush or broom comprising my invention. 50 Fig. 2 is a transverse section of the same taken on the dotted line $x-x$ in Fig. 1. Figs. 3 and 4 are details of the means employed for securing the rows of brushes to the frame of the broom. Fig. 5 is a detail of the 55 broom frame-work employed where three or

more independently movable sections or brooms embodying my invention are mounted on a common shaft. Fig. 6 is an end view of the inner broom section of Fig. 5. Fig. 7 is a central transverse section, and Fig. 8 an end view of one of the hubs of a broom section, and Fig. 9 is a fragmentary end view of a street sweeping machine and a central longitudinal section of my invention adjusted in position to clean a gutter.

Referring to the drawing, 5 represents a shaft on which one or more sections of the broom comprising my invention are mounted the number of such sections depending upon the requirements of the use to which it may be applied. The skeleton or frame of a broom section comprises the two circular end castings 8 and the bracing-rod 11, which latter have their ends rigidly secured to said castings and retain them in properly-spaced position. The periphery of each casting 8 is formed with a plurality of equi-distant transverse pockets 8^a for receiving the ends of the steel brushes 12 and fiber brushes 13, which are alternately arranged around the same, as shown in Fig. 2. These brushes are each formed by looping the steel or fiber, as the case may be about a retaining rod 12^a and clamping the looped portions rigidly against the retaining rod by means of the longitudinal clamping-plates 12^b. The pockets 8^a in which the steel brushes are secured each have their outer faces formed with a slot 8^b a portion of their depth, as shown in Fig. 7, to enable the outer ends of the rods 12^a of the steel brushes to extend therethrough, and are rigidly locked against movement in said pockets by means of a tightening band 12^c, which surrounds the ends of said rods, as shown. The band 12^c is retained in position on said rods by reason of the extremities of each rod being bent at a right angle to form a lip 9^c thereon.

In the construction of the brooms of my machine both steel and fiber brushes are employed, as the former operates to free the dirt and packed adhesive substances from the surface of the pavement, and the latter operates to lift and set in motion the dust and finer particles of dirt so that they may be lifted and drawn within a conduit associated with the machine by the action of an air-draft created therein. These different brush substances are arranged in alternate rows around the peripheries of the connected cast- 100 105 110

ings 8, the fiber brushes having their ends terminating within the pockets 8^a and being secured therein as hereinafter described, and the steel brushes having their retaining rods 12^a passed through and terminating without the slots 8^b in said end castings and being secured therein, as above described.

A sleeve 14 is loosely carried by the shaft 5 intermediate of the end castings 8 of each broom section and has its ends threaded, as shown at 14^a, to receive the internally-threaded collars 14^b. A number of rods 14^c, corresponding to the number of fiber brushes 13 employed in a broom section, are pivotally secured at one end to a peripheral flange or shoulder on each of the collars 14^b and have their outer ends pivotally attached to the metal clamping strips 12^b of said brushes near the outer ends thereof, thereby causing the fiber brushes 13 to be raised or lowered within the pockets 8^a as the collars 14^b are moved away from or toward each other by turning the sleeve 14. The sleeve 14 is rotated by means of a pinion 15, which is carried by the shaft 15^a and meshes with a gear 14^d, formed on the sleeve 14, the said shaft having its outer end extended through a bearing provided in one of the end castings 8 and squared to receive a winding key or crank. A metal band 16 encircles and is rigidly secured to the bracing-rods 11 of a broom section in centrally-disposed position with relation to the sleeve 14 and has the radial pins 16^a rigidly projecting therefrom with their inner ends loosely resting in a peripheral groove 16^b on said sleeve, thereby preventing a longitudinal movement of the sleeve 14 on the shaft 5. It will thus be seen that as the fiber brushes 13 wear and become shorter than the steel brushes, which is occasioned by reason of the softer character of the former, the said fiber brushes may be raised a sufficient distance to bring the outer edges thereof in a plane with those of the contiguous steel brushes.

In the operation of machines, for instance, such as street sweepers, in which rotary brushes are employed it is found that some provision should be made whereby the broom sections may each be permitted to have a lateral movement independent of the shaft on which they are mounted to accommodate themselves to any unevenness in, or the changing contour of, a pavement. I accomplish this by forming the hubs of each end casting 8 with enlarged bearing apertures 9, so that the shaft 5 rests loosely therein to permit of a desired amount of lateral play, as shown. The broom sections are caused to revolve with the shaft 5 by reason of the bearings 9 of the outer end castings of the associated sections being provided with recesses or grooves for receiving the cogs or spurs of a pinion 10, which is keyed to the shaft, as shown in Figs. 5, 7 and 8. Should it be de-

sired to employ more than two broom sections, as shown in Fig. 5, the inner brush sections are revolved by means of a series of pins 17, which project from the inner end castings 8 of the outer broom sections and loosely operate within sockets 17^a, formed on the contiguous ends of the inner sections. The sockets 17^a are made sufficiently large to permit of the ends of the inserted pins to have a lateral play therein to allow for the independent lateral movement of the broom sections as they follow the changing contour of the pavement.

The broom-shaft 5 is made longitudinally extensible to enable it to carry a gutter broom should it be employed in a street sweeping machine, as shown in Fig. 9. In this figure 18 represents portions of the framework of a street sweeping machine from either side of which are suspended the brackets or hanger-arms 19. In these two brackets is journaled a shaft 20 having the forwardly-projecting arms 21 loosely pivoted thereto, both of which have bearings provided in their forward extremities, in one of which is mounted the broom-carrying shaft 5 and in the other a longitudinally alining shaft section 5^a. The inner end of the shaft section 5^a is provided with a peripheral flange 22 and with an axial socket 22^a, which latter is adapted to receive the contiguous end of the shaft 5 when in normal position, and be rigidly secured thereto by a bolt or cotter pin. The extension of the shaft 5 is accomplished by securing a peripherally-flanged sleeve 23 to the inner end of the shaft 5 and then inserting a shell 24 of suitable length between the contiguous ends of the shaft 5 and section 5^a, the end pieces 24^a of the shell being securely bolted to the flanges on the end of the shaft section 5^a and the sleeve 23. A coiled compression spring 25 is mounted in the shell 24 with its ends in abutting position against the end pieces 24^a of the shell, and is adapted to permit of a longitudinally yielding movement of the shaft 5 and associated broom sections when the flanged binding nut 26, which is threaded to the outer end of the shaft 5, comes in contact with a curbstone or other obstacle. The shell 24 is permitted to have a limited sliding movement with respect to one of its end pieces 24^a by reason of a series of lugs or pins 27 on such end piece operating within the elongated slots 27^a provided in said shell. The bearing arm 21 in which the shaft 5 is mounted is also permitted to have a longitudinal movement with the shaft 5 by reason of its sliding on the shaft 20.

Numerous ways may be provided for removing one of the broom sections from between the arms 21 to enable the shaft 5 to be extended and then placing it on the extended end thereof, one method being to remove the inner broom section from the severed end of the shaft prior to the placing of the sleeve 23

thereon and then mounting it on the outer extended end of the shaft.

Having thus described my invention, what I claim as new and desire to secure by Letters Patent, is—

1. A rotary broom having two spaced end castings provided with radially-disposed peripheral pockets, a plurality of steel brushes and fiber brushes having their ends mounted in alining pockets in the opposite end castings, the fiber brushes being movably mounted and the steel brushes rigidly mounted in their respective pockets, and means within the broom having connection with each fiber brush for radially adjusting said fiber brushes.
2. A rotary broom comprising a shell, a plurality of steel brushes and fiber brushes circumferentially mounted on said shell, the fiber brushes being radially adjustable, rotatable means mounted within the shell and having connection with the fiber brushes for causing an adjustment of said brushes, when said means is turned, and means for imparting rotation to said means.
3. A rotary broom comprising a shaft, a plurality of steel brushes and fiber brushes, a sleeve loosely mounted on the broom-shaft internally of said broom; collars threaded to the ends of said sleeve, connecting rods pivoted to the collars and fiber brushes whereby said fiber brushes are adjusted by a longitudinal movement of said collars, and means for rotating said sleeve to move said collars.
4. A shaft comprising two separable sections capable of having their inner ends placed in abutment and secured together, one of said sections being longitudinally adjustable in its bearing, bearings for the shaft sections, a spacing member removably secured between the contiguous ends of the shaft sections whereby to cause a portion of the adjustable section to be extended without its bearing, and a broom carried by the extended end of the shaft.
5. A rotary broom consisting of rigidly spaced end castings having radially-disposed peripheral pockets, a plurality of brushes having their ends mounted in the alining pocket in said castings and having portions extending beyond the faces of said castings, a band at the outer side of each casting for engaging the extended portion of the brushes whereby to lock the brushes in the pockets.
6. A rotatable shaft, a broom comprising rigidly connected end castings mounted on said shaft and having radially elongated pockets provided in the periphery thereof, a series of brush sections rigidly secured in a portion of said pockets, a second series of brush sections adjustably secured in others of said pockets, and means inclosed within the broom for radially adjusting said latter brush sections.
7. The combination with a shaft, of a

broom carried by said shaft having its shaft-receiving opening of greater diameter than that of the shaft and provided with recesses extending from the said opening, and a pinion carried by the shaft and having its teeth loosely meshing with the recesses in the shaft-receiving opening of the broom whereby to impart rotation to and permit of lateral play of the broom on the shaft.

8. A shaft comprising two separable sections, one of which sections is longitudinally adjustable in its bearing, a bearing for each shaft section, a longitudinally yielding spacing member removably secured between the contiguous or inner ends of the shaft sections whereby to cause a portion of the adjustable shaft section to extend without its bearing, and a broom mounted on the extended end of the shaft.

9. Two shaft bearing members, a sectional shaft having one section mounted in one bearing member and prevented from longitudinal movement therein and the other section mounted to have a longitudinal movement in the other bearing member, means secured between the contiguous ends of the shaft sections whereby a portion of the longitudinally movable section is extended beyond its bearing, and a rotary broom mounted on the extended section.

10. A rotary broom carrying shaft comprising two separable sections, one of which is longitudinally movable in its bearing, bearings in which the shaft sections are mounted, a spacing member secured between the contiguous ends of the shaft sections whereby to cause a portion of the longitudinally movable section to extend beyond its bearing, said spacing member comprising a shell having relatively movable ends, and yielding means inclosed within the shell in abutment with its ends, and a broom mounted on the extended end of the shaft.

11. A rotatable broom-shaft, a broom mounted on said shaft and comprising a series of sections, said sections each having their bearing openings of greater diameter than said shaft to permit of independent lateral play thereon, rigid means mounted on said shaft for loosely engaging the hubs of the outer broom sections for imparting rotation thereto, sockets provided in the hub portions of the inner broom sections, and pins projecting from the inner faces of the outer broom sections and extending loosely within the sockets in the contiguous ends of the inner broom section to impart rotation thereto and permit a limited independent lateral play of the sections.

12. A rotary broom carrying shaft comprising two separable sections, one of which is longitudinally movable in its bearing, a bearing for each shaft section, yielding spacing means removably secured between the contiguous ends of the shaft sections, said

means comprising a shell having its ends relatively movable axially of the shaft and secured to the contiguous ends of the shaft sections whereby to permit of a slight longitudinal movement of the extended section, and a spring mounted within the shell with its ends abutting the shell ends, and a broom section carried by the extended shaft section at each side of its bearing.

13. The combination with a shaft, the bearings therefor, and means for extending a portion of the shaft beyond one of the bearings, of a broom mounted on the extended portion of the shaft and having its shaft receiving opening of greater diameter than the shaft whereby to permit of lateral play on

the shaft, and means for causing the broom to revolve with the shaft.

14. In combination, a rotary broom having an axial opening therethrough, a shaft 20 extending through said opening and being of less diameter than said opening whereby to permit of lateral play of the broom thereon, bearings for the shaft, and means for causing the broom to revolve with the shaft. 25

In testimony whereof I have hereunto signed my name to this specification in the presence of two subscribing witnesses.
